UNITED STATES PATENT OFFICE.

ROSS W. TULLOCH AND PIERRE BARNES, OF SEATTLE, WASHINGTON.

POWER SET-WORKS FOR SAW-CARRIAGES.

SPECIFICATION forming part of Letters Patent No. 777,318, dated December 13, 1904.

Application filed November 23, 1903. Serial No. 182,342. (No model.)

To all whom it may concern:

Be it known that we, Ross W. TULLOCH and PIERRE BARNES, citizens of the United States, residing at Seattle, in the county of King and State of Washington, have invented certain new and useful Improvements in Power Set-Works for Saw-Carriages, of which the following is a specification, reference being had therein to the accompanying drawings.

10 This invention relates to power-actuated set-works for sawmill-carriages; and the object of our invention is the provision of a simple, inexpensive, but effective apparatus for advancing or receding expeditiously the knees upon the head-blocks of a saw-carriage.

The several features of our invention and the advantages arising from their use, conjointly or otherwise, will be apparent from the following description, taken in connection 20 with the accompanying drawings, in which—

Figure 1 is a longitudinal elevation of a saw-carriage to which our invention is applied, and Fig. 2 is a plan view of the same. Fig. 3 is an enlarged horizontal section of power-transmission devices shown in the preceding views. Fig. 4 is a vertical transverse section taken on line *xx* through a head-block, wherein is shown a knee actuated by a screw-shaft. Fig. 5 is a similar view on line *yy* of Fig. 6, 25 wherein a knee provided with a rack is actuated by a pinion upon the set-shaft; and Fig. 6 is a plan view, partly in section, of the invention applied to such an arrangement.

Similar reference characters indicate corresponding parts in all of the views.

The numeral 2 represents a saw-carriage having supporting-wheels 3, which travel on track-rails 4, laid upon the mill-floor. The carriage is provided with transversely-arranged 40 head-blocks 5, upon which are positioned knees 6, which are reciprocally movable thereon and transversely of the carriage by a longitudinally-disposed rotatable set-shaft 7.

The motion of the set-shaft is usually communicated to move the knees either by spur-pinions 8 upon the said shaft, which engage with racks 9, provided upon the respective knees, as plainly shown in Figs. 5 and 6, or by screw-shafts 10, provided for the several 45 head-blocks and which respectively engage with a registering nut 10', integrally connect-

ed to each knee, and the said screws are rotated in unison from the set-shaft by miter-gears 11. (See Figs. 1, 2, and 4.)

The application of the invention to the last-referred-to construction—that is, screw devices—which is most commonly used in those sections of the country where big timber is cut and where power set-works are most needed, 55 will now be described.

Extending transversely of the carriage and journaled in suitable boxes, such as 12, rigidly secured thereto, is a power-shaft 13, which is driven by suitable means, such as an endless cable 14, traveling continuously about sheaves 65 15 and 16 upon counter-shafts 15' and 16', respectively, and preferably positioned at such a distance beneath the mill-floor that the sheaves will protrude thereabove and deliver the cable in line with the fair-leaders or idler-sheaves 70 presently referred to. Either of the said sheaves may be the driver, and a tightener device, such as a sheave 17 on a movable shaft 17', is advantageously utilized to insure an effective tension or grip of the cable upon the 75 driving-sheave aforementioned and a sheave 18, which is fixedly mounted upon the said power-shaft.

The idler-sheaves 19, mounted upon axles or shafts 19', journaled in boxes 19", are arranged to deflect the cable for the purpose of increasing the length of circumferential contact with the sheave 18 and also guide the cable so that it will travel close to the floor.

Driving and driven elements 20 and 21, respectively, are mounted upon the power-shaft and the set-shaft or upon an intermediate shaft and consist in the construction illustrated of intermeshing bevel-tooth gear-wheels, the driving element being keyed or otherwise secured to the power-shaft, while the driven elements are mounted normally loose upon their shaft and positioned upon diametrically opposite sides of the power-shaft axis and in consequence are rotated in opposite directions 90 and coincidently with the power-shaft. We preferably use two of said driving elements of different diameters in order to impart a higher rate of travel when receding than when advancing the knees; but when under peculiar 95 conditions this may be deemed to be unimportant a single driving element, as shown in 100

Fig. 6, would be the less expensive construction. Any suitable clutch device capable of independently engaging either of the driven elements to its shaft may be used to impart a 5 rotary motion to the latter from the power-shaft; but we prefer the one illustrated in the drawings comprising a sleeve 22, splined to the set-shaft, so as to integrally rotate therewith, but be movable axially thereof, and provided with conical-shaped ends 23, which respectively register with recesses 24, provided in the opposing ends of the driven elements. The longitudinal movement of the said sleeve or clutch member is controlled by suitable 15 means—such as a shifting-lever 25, fulcrumed at 25', and which is pivotally connected by studs 26 with a collar 27, seated in a peripheral groove 28 in the said sleeve. The lever may be provided with a handle for the attendant to grasp in shifting the sleeve, though for convenience in operation the said lever is preferably connected with a supplemental or working lever 29 by a reach-rod 30, provided with a turnbuckle 30' for adjusting its length. 25 31 is a sector-plate having a notch 32 therein so disposed as to engage a spring-actuated locking-bolt 33, carried by the lever 29, and normally retain the clutch-controlling connections in such positions that the sliding clutch 30 member will be at its inoperative position—that is to say, disengaged from the driven elements.

34 represents set-collars provided to prevent the end thrust received from the sliding clutch member from displacing the said driven elements when being coupled to the shaft.

Where it is desirable to make a further reduction of speed than can conveniently be accomplished by a single pair of gears—as, for 40 instance, with the pinion and rack sets—an intermediate shaft 35, with suitable transmission-gear 36, (see Fig. 6,) may be included in the connection between the power and set shafts.

45 The operation of the invention is as follows: The cable, traveling continuously, rotates the power-shaft and also through the driving element thereupon the normally loose driven elements in reverse directions upon the set-shaft. When the knees are to be advanced or receded, then the driven element which will impart the required forward or backward motion thereto is engaged to the shaft by simply thrusting the sliding clutch member 50 into operative engagement therewith. It should be mentioned that where provision is made for rotating the set-shafts at different speeds the slower motion should be utilized for advancing the knees, as greater precision 55 or accuracy can thereby be attained in successively setting forward the saw-log to distances equal to the thickness of the required cuts, while oftentimes—as, for example, when a new log is to be received upon the carriage—it is important that the backward move-

ment of the knees should be attained with celerity, thereby minimizing the loss of time, as is inherent in the use of all such apparatus for this purpose heretofore in use and within our knowledge, and which is accomplished through this invention by the use of the means for receding the knees at a relatively high rate of speed. 70

Having thus described our invention, what we claim as new, and desire to secure by Letters Patent, is—

1. In a power set-works for saw-carriages, the combination of a power-shaft and means for rotating the same, toothed bevel-gears fixedly secured to said power-shaft, a set-shaft arranged at right angles to said power-shaft, a pair of oppositely-disposed toothed bevel driven gears loosely mounted upon the set-shaft and meshing with said driving-gears continuously, a sleeve splined upon said set-shaft intermediate the gears thereof, clutch elements carried by said sleeve co-operating with clutch elements carried by said driven gears, and means for sliding said sleeve. 80

2. In a power set-works for saw-carriages, the combination of a power-shaft and means for rotating the same, toothed bevel-gears fixedly secured to said shaft, said gears being of different diameters, a set-shaft arranged at right angles to said power-shaft, a pair of oppositely-disposed toothed bevel-gears loosely mounted upon the set-shaft and being continuously in mesh with the first-named gears, the driven gears having their body portions formed with conical recesses, a sleeve splined to the set-shaft between the last-named gears, said sleeve having conical ends adapted for alternate reception in the conical recesses of said gears, and a handle operatively connected to said sleeve for sliding the same. 90

3. In combination with the frame, and a plurality of transversely-arranged screw-shafts journaled therein, said screw-shafts projecting beyond one side of the frame and being provided with gears, a set-shaft journaled without the frame and being arranged at right angles to said screw-shafts, gears on said set-shaft meshing with the first-named gears, a power-shaft journaled in the frame parallel to the screw-shafts, and having one of its ends projecting beyond one of the frame sides, a bevel-gear fixedly secured to the projecting end of said power-shaft, similar gears loosely mounted on the set-shaft and meshing therewith, and a clutch device mounted on the set-shaft between the gears thereof whereby either of said gears can be engaged with the set-shaft. 100

In testimony whereof we affix our signatures in presence of two witnesses.

ROSS W. TULLOCH.
PIERRE BARNES.
